UNITED STATES PATENT OFFICE

GEORGE J. MEYER, OF MILWAUKEE, WISCONSIN, ASSIGNOR TO GEO. J. MEYER MANUFACTURING COMPANY, OF MILWAUKEE, WISCONSIN, A CORPORATION OF WISCONSIN

WASHING APPARATUS

Original application filed January 24, 1925, Serial No. 4,455. Patent No. 1,787,993, dated January 6, 1931.
Divided and this application filed September 17, 1927. Serial No. 220,141.

The invention relates to bottle cleaning machines, more particularly to that type in which the bottles are subjected to cleaning operations during the intervals of rest in 5 the intermittent travel of the bottles.

An object of the invention is to provide a bottle cleaning machine including simple and inexpensive pumping means for furnishing timed bottle washing and rinsing sprays, 10 thereby rendering it possible to finally rinse the bottles with water other than that furnished by the usual water supply, such as a sterilizing solution, or to furnish both washing and rinsing sprays when the necessary 15 water pressure is not available on service mains, and in other cases to reclaim the rinsing water from the final spray for use in other sprays.

Another object of the invention is the provision of pump operating means whereby several successive sprays are furnished to the bottles during each pause in the travel of the bottle conveyor.

A further object of the invention is to provide a bottle cleaning machine having simple and durable means for smoothly controlling the intermittent travel of the conveyor advancing the bottles through the machine.

A further object is to provide a bottle cleaning machine including guide members between which the bottles travel in inverted position for preventing their lateral deflection.

The invention further consists in the several features hereinafter set forth and particularly defined by the annexed claims.

This application constitutes a division of my co-pending application for bottle cleaning machines, Serial No. 4,455, filed January 24, 1925.

In the accompanying drawings, Fig. 1 is a fragmentary side elevation of a bottle cleaning machine embodying the invention;

Fig. 2 is a fragmentary sectional view taken on the line 2-2 of Fig. 1;

Fig. 3 is a detail view of the bottle conveyor impelling means;

Fig. 4 is a detail sectional view taken on 50 the line 4-4 of Fig. 3;

Fig. 5 is a top plan view of a group of bottle guiding members;

Fig. 6 is a transverse sectional detail view through the machine showing the bottle guiding members;

55

Fig. 7 is a detail end view of one of the bottle guiding members; and

Fig. 8 is a fragmentary detail elevation of the control mechanism for the bottle conveyor impelling means.

60

In these drawings the numeral 25 designates a frame of suitable construction supporting angle and channel guides 26 on which travel the rollers 27 of conveyor chains carrying transversely-extending rows of bottle-holding pockets 28, as seen in Figs. 2 and 6. The bottle conveyor thus formed is moved intermittently, step by step, by impelling means 29, hereinafter more particularly described, engaging the chains for moving the conveyor in its guides in the direction indicated by arrows. The conveyor includes upper and lower horizontal flights, which move in opposite directions, and a descending vertical flight at one end of the 75 machine adjacent which loading and unloading devices 30 and 31, respectively, are disposed for attention by the same operator.

The lower horizontal flight of the conveyor travels through a soaking tank 32 containing a cleaning solution in which the upright bottles 38 are soaked during their travel toward the ascending flight of the conveyor (not shown). The bottles entering the solution in a horizontal position in which they are partly filled and are then turned to an upright position in which they are completely filled. The intermittent travel of the bottles through the tank causes agitation of the solution of the bottles surrounding them which aids in loosening the labels.

80

In their further travel to the upper flight of the conveyor, the bottles become inverted and are emptied of their solution, which is returned to the tank.

85

After thorough draining, the bottles are rinsed and raised out of the conveyor pockets 28 to project them against and between rotary cleaning brushes 34 for outside and bottom cleaning, as more particularly dis-

100

closed and described in the co-pending application Serial No. 7,862 of George J. Meyer, et al., filed February 9, 1925, which has matured into Patent No. 1,817,014 5 granted August 4, 1931. Following the outside brushing, rotary brushes 35 enter the bottles for inside cleaning. The bottles are then rinsed thoroughly and allowed to drain during the remainder of their travel so that 10 they are practically dry by the time they are discharged at the descending end of the conveyor, as hereinafter described.

In the present instance the last rinsing operations are accomplished by pumping 15 apparatus including a plunger pump 134 for furnishing rinsing sprays. The pump includes a pump barrel 136 in which reciprocates a plunger or piston 137 pivotally connected to a reciprocatory plunger rod 20 135. A conduit 138, having therein a check valve 140, leads from the pump barrel 136 up to apertured rinsing spray pipes 139 disposed below the necks of some of the inverted bottles in the upper flight of the bottle 25 conveyor. A reservoir 141 is connected to the pump barrel 136 by a conduit 142 which includes a check valve 143.

Upon the suction stroke of the pump water is drawn from the reservoir 141, the 30 check valve 140 being then closed, and upon the succeeding pressure stroke of the pump the check valve 143 closes, while the check valve 140 is open, and water is then delivered under pressure through the conduit 138 and 35 to the spray pipes 139 below the then stationary bottles 38. Rinsing sprays are thus projected into the bottles, and the water draining from the bottles is collected in a tray 144, whence it returns through a pipe 40 144' to the reservoir 141 for further use. With the above arrangement the sprays furnished by the rinsing pipes 139 are the final rinsing sprays and the water used for such sprays preferably contains a sterilizing 45 agent in solution. Since the same water can be used repeatedly the sterilizing operation is carried out economically.

In order to obtain a pressure stroke of the 50 pump plunger at a time when the bottles in the intermittently moving conveyor are stationary, the plunger rod 135 co-operates with the impelling mechanism for the bottle conveyor. The impelling mechanism in the present instance includes a pair of reciprocating pusher bars 29 at opposite sides of the machine pivoted to arms 145 secured to a rock shaft 146. The pusher bars have hooked free end portions 147 to engage the rollers 27 of the conveyor chains and each 55 pusher bar carries near its hooked end a lifter member 148 having a laterally extending flange 149. A groove 150 is formed longitudinally in the under side of the flange and the forward end of the flange is preferably upwardly curved. Rocker arms 151

are secured at opposite ends of a rock shaft 152 journalled in the frame of the machine and operated in any suitable manner, as by a rotary cam 152'. Each rocker arm carries a roller 153 engageable with the under side 70 of the flange 149 of the pusher bar lifter member 148, a peripheral flange 154 on the roller being disposed in the groove 150 in the lifter member to prevent lateral movement of the free end of the pusher bar. 75

A bell crank 170 is secured at one end of the rock shaft 146 and one arm of the bell crank is connected to a link 171 which has its other end pivotally mounted on an eccentric portion of a wheel 172 carried on a shaft 173, which latter is thus constituted a crank shaft. The other arm of the bell crank 170 is connected to the plunger rod 135 for effecting the reciprocation of the plunger 137 of the plunger pump, the parts 80 being so related that the plunger 137 is on its pressure stroke every time the pusher bars 29 are being retracted and on its suction stroke every time the pusher bars are projected forwardly. The crank shaft 173 85 is driven continuously by any suitable means and has a gearing connection 174 with a cam shaft 175 which carries the cam 152', the gearing connection being such that the crank shaft rotates faster than the cam 90 shaft by some multiple. In the present instance, the crank shaft rotates three times as fast as the cam shaft so that the plunger pump through its linkage with the crank shaft 173 is given three working strokes for 95 every revolution of the cam shaft, which latter in each revolution controls and effects one washing cycle. During the greater part 100 of each washing cycle, namely five-sixths, the bottle conveyor is stationary so that the then stationary bottles therein may receive various cleaning operations, all of which, among others, are controlled directly or indirectly from the cam shaft 175. During 105 this interval the hooked ends of the reciprocating chain pusher bars 29 are kept elevated out of operative connection with the conveyor chains by means of the rocker arms 151 mounted on the rock shaft 152, the lifter member 148 of each pusher bar riding in 110 elevated position on the roller 153 of the adjacent rocker arm 151 as the pusher bars describe two forward and three backward strokes. During each interval in which the 115 bottles are stationary the plunger pump is given three working strokes so that the bottles receive therefrom three rinsing spray injections in each washing cycle. Following the last of these spray injections the 120 rocker arms 151 are depressed, which places the hooked ends of the pusher bars in engagement with the conveyor chains so that during the succeeding suction stroke of the 125 pump the pusher bars 29 are on their conveyor-impelling stroke. After this stroke 130

the rocker arms 151 are again elevated to lift the pusher bars out of operative engagement with the chain, whereupon the bottles are again subjected to various operations while the conveyor is stationary.

The three-cycle crank shaft 173, through the intermediate crank motion and pusher bars, imparts to the bottle conveyor a rapid but easy movement, the conveyor being smoothly accelerated and decelerated. The use of the crank motion insures long life with little attention, and permits the movement of the conveyor in one-sixth of the cycle of operation, thereby affording a relatively long time interval for brushing and rinsing operations.

While in the present instance the pumping means is employed to furnish sterilizing sprays from continuously reclaimed sterilizing solution, it is also possible to employ this pumping means in various other ways; for instance, to furnish both washing and rinsing sprays when the necessary water pressure is not available on service mains, and in other cases to reclaim the rinsing water from the final spray furnished from service mains, and to use said reclaimed water, which is now slightly warmer, for other sprays. It will be apparent that the pumping means can be employed, if desired, to serve the entire machine with timed washing and rinsing sprays, especially in those cases where a water supply under pressure is not available or is unsuitable for the purpose.

In order to insure the proper registration of the bottles with the spray pipes and brushes, guide or separator strips 158 are disposed longitudinally below the upper flight of the bottle conveyor, these guide strips being laterally spaced to receive the neck portions of the inverted bottles between them, as seen in Figs. 5 and 6, and mounted at opposite ends on pedestals 180, which are secured to transverse frames or supports 159 carried on the main frame 25 of the bottle washing machine. The pedestals 180, more remote from the loading station, are provided with pointed heads 160 forming extensions of the guide strips, as seen in Figs. 5 and 7, to properly guide the necks of the bottles entering the slots between the guide strips. Each slot includes an enlarged portion at an intermediate point in order that the bottles descending after their brushing operation may have an opportunity to return properly into the slot should the necks of such bottles be deflected laterally a sufficient amount so that they rest on the edge portions of the guide strips.

The operation of unloading clean bottles from the descending portion of the bottle conveyor takes place simultaneously with the loading operation and at substantially the same location, in order that the same attend-

ant may supervise both operations and to conserve space at the opposite end of the machine. As the conveyor comes to rest to receive a row of bottles from the loading means 30, a transversely extending bar 58 is swung forwardly on pivotally mounted supporting arms 59 to engage a row of bottles at their necks and thus eject these bottles in substantially horizontal position from the row of bottle-holding pockets, this row of pockets being in the descending portion of the conveyor a short distance above the point at which the bottles are loaded onto the conveyor. To receive the bottles as they leave the conveyor pockets pivotally mounted inclined bottle guides or chutes 60 are included in the bottle unloading means.

What I claim as new and desire to secure by Letters Patent is:

1. In a bottle washing machine, the combination of an intermittently-traveling bottle conveyor adapted to hold bottles in inverted position, conveyor-impelling means, a spray conduit disposed to register with the openings of said bottles during pauses in their travel, a plunger pump connected to said conduit including a plunger operatively connected with said conveyor-impelling means to be movable on a pressure stroke during pauses in the travel of said bottle conveyor for injecting a fluid spray into said bottles, and means for supplying fluid to said pump.

2. In a bottle washing machine, the combination of a traveling conveyor adapted to hold bottles thereon, conveyor-impelling means for intermittently moving said conveyor, a conduit for spraying said bottles with fluid during the pauses in the travel of the bottle conveyor, a fluid pump connected to said spray conduit and including a reciprocating member, and means operatively connected with said conveyor-impelling means for moving said reciprocating member on a plurality of spray-producing strokes during each pause of the bottle conveyor.

3. In a bottle washing machine, the combination of a traveling conveyor adapted to hold bottles thereon, impelling means for intermittently moving said conveyor, a conduit for spraying said bottles with fluid during the pauses in the travel of the bottle conveyor, and a plunger pump connected to said conduit and including a plunger operatively connected with said impelling means for movement on a plurality of spray-producing strokes during each pause in the travel of the bottle conveyor.

4. In a bottle washing machine, the combination of a traveling conveyor adapted to hold bottles thereon, conveyor-impelling means including a reciprocating member movable in one direction on its conveyor-impelling stroke and in the other direction

- on an idle stroke, a conduit for furnishing fluid sprays to said bottles during the pauses in their travel, a pump connected to said conduit and including a plunger, and an operative connection between said pump plunger and conveyor-impelling means for moving said plunger on its pressure stroke while said reciprocatory impelling member is on its idle return stroke
- 10 5. In a bottle washing machine, the combination of a bottle conveyor, a shaft rotatable one revolution for each cycle of operation of the machine, a multiple revolution shaft having a gearing connection with said one-cycle shaft, crank-operated impelling means for said conveyor driven by said multiple revolution shaft and including a reciprocatory impelling member having an intermittent impelling connection with said conveyor, means operatively connected with said one-cycle shaft and acting on said conveyor-impelling means for rendering said reciprocatory member ineffective to move said conveyor during all but one stroke thereof for each cycle of operation of the machine, and a reciprocating pump having a connection with said multiple revolution shaft for furnishing a plurality of bottle-washing sprays during each cycle of operation of the machine.
